SWITCH AND SWITCH STAND FOR MODEL RAILROADS

Chester A. Erickson, Denver, Colo.

Application June 21, 1948, Serial No. 34,263

3 Claims. (Cl. 246—412)

1

This invention relates to a switch and switch-stand for model railroads, and has for its principal object the provision of a neat and highly efficient switch mechanism which will simulate the action of a standard railroad switch, by having a switch stand which will rotate 90° so as to give signal indications; and which will efficiently operate the track switch points.

Another object of the invention is to so construct the device that the track switch points will be resiliently maintained in snug rail engagement at both positions of the switch.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved model railroad switch; and

Fig. 2 is a side view thereof, looking on the line 2—2, Fig. 1.

Model railroads are usually built upon a board, bench or table top, or other supporting flat surfaces, such as indicated at 10 on the drawing. A road bed strip 11 is usually secured on the platform 10, and model ties 12 are secured on the bed 11. The ties support an outer main rail 13 and an inner main rail 14.

Two movable rail switch points 15 are positioned between the rails 13 and 14 and held in spaced relation by means of a spacer plate 16 soldered or otherwise secured to the points 15, as in the usual model railroad split switch construction.

The improved switch consists of a switch stand 17, from which a standard 18 arises carrying a switch target 19 and a model signal lantern 20 provided with colored jewels simulating the red and green signal lenses of a railroad switch stand. The lower extremity of the stand 17 is reduced in diameter to form a threaded stud 21. The stud 21 is inserted in a cylindrical bushing sleeve 22 which is forced into a receiving hole in the platform 10 so as to be rigidly held in place therein.

The threaded extremity of the stud 21 projects downwardly below the bottom of the platform 10 and is provided with two lock nuts 23 and 24 and a spring lever arm 25. The extremity of the spring lever arm 25 is turned downwardly and

2

notched to receive one extremity of a tension spring 26. The other extremity of the spring 26 is secured to a downwardly depending arm 27 on an angle bracket 28. The angle bracket 28 is secured beneath the bottom of the platform 10 by means of a suitable screw 29, and its vertical arm 27 is notched to properly position the spring 26 thereon.

A handle 30 and an operating lever 31 project radially from the switch stand 17. The extremity of the lever 31 is turned upwardly so as to project through an elongated curved slot 32 in a link member 33. The link member 33 is secured at one extremity, by means of a pivot rivet 34, to a strap 35 which passes beneath the spacer plate 16 and is secured thereto by means of an attachment screw 36.

The relation between the position of the switch stand 17, the length of the slot 32, and the spacing between the switch points 15 and the rails 13 and 14 is such, that when the operating lever 31 swings from one extremity of the slot 32 to a position against the other extremity thereof the switch stand 17 will have rotated 90° so as to place the target 19 and the lantern 20 in the two signal positions. The spring 26 acts to retain the arm 31 against the extremities of the slot 32.

The position of the screw 29 and the switch stand is such that the spring 26 will swing past the dead-center position when the switch stand 17 has been rotated 45° so that the remaining tension in the spring will serve to snap the arm against the other extremity of the slot 32 so as to firmly and resiliently maintain the points 15 against their respective rails 13 and 14.

The strap 35 is of a width to fit closely between two of the ties 12 so as to be guided by the latter transversely of said strap.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A switch for model railroads of the type mounted on a platform, comprising: two outside rails; two switch points arranged to reciprocate between said outside rails; a spacer plate extending between and secured to both switch points; connecting means secured beneath said spacer plate and extending outwardly beyond one of the outer rails; a switch stand positioned alongside said connecting means and extending downwardly through said platform so

as to project below the latter; an operating lever fixedly secured to and extending radially outward from said switch stand above said platform and through an arcuate, longitudinally positioned slot in said connecting means; a handle fixedly secured to and projecting from said switch stand above said operating lever for manually rotating said stand; a radially extending spring arm affixed on the lower extremity of said switch stand below said platform so as to swing with the rotation of said stand, said spring arm being positioned substantially in vertical alignment with said operating lever; spring attachment means secured to and beneath said platform on the opposite side of said stand from said spring arm; and a tension spring extending between the free extremity of said spring arm and said attachment means and positioned so as to swing across and beneath said stand when said stand is rotated to resiliently hold said switch points against either outside rail.

2. A switch for model railroads of the type mounted on a platform, comprising: two outside rails; two switch points arranged to reciprocate between said outside rails; a spacer plate extending between and secured to both switch points; connecting means secured beneath said spaced plate and extending outwardly beyond one of the outer rails; a switch stand positioned alongside said connecting means and extending downwardly through said platform so as to project below the latter; an operating lever fixedly secured to and extending radially outward from said switch stand above said platform and through an arcuate, longitudinally positioned slot in said connecting means; a handle fixedly secured to and projecting from said switch stand above said operating lever for manually rotating said stand; a radially extending spring arm affixed on the lower extremity of said switch stand below said platform so as to swing with the rotation of said stand, said spring arm being positioned substantially in vertical alignment with said operating lever; spring attachment means secured to and beneath said platform on the opposite side of said stand from said spring arm; and a tension spring extending between the free extremity of said spring arm and said attachment means and positioned so as to swing across and beneath said stand, the length of said slot being sufficient to allow said stand and its operating lever to be manually rotated without imparting movement to said con-

necting means until said spring has been swung to the opposite side of said stand, at which time said spring will come into action to bring said switch points in resilient engagement with their respective rails.

3. A switch stand for operating model railroad switches of the type having two switch points arranged to reciprocate between two track rails mounted on a platform, comprising: a switch stand positioned at one side of said rails, said stand being rotatably mounted in an opening in said platform and extending above and below the latter; a link member extending from said switch points to a position alongside said switch stand; an operating lever secured to and projecting radially from said switch stand to said link member, there being an elongated slot in said link member at the extremity of said lever; attaching means on the extremity of said lever mounting the latter for longitudinal movement in said slot; a radially extending spring arm secured on said switch stand below said platform; a tension spring extending from the free extremity of said spring arm; a spring bracket secured to the extremity of said spring; means attaching said bracket to the bottom of said platform at a position to cause said spring to swing back and forth across the axis of said switch stand and below the latter as said stand is rotated, said slot being sufficiently long to allow said stand to be manually rotated through an arc to swing said spring to opposite sides of said stand without imparting movement to said link member, and sufficiently short to allow the spring to snap the operating lever against the opposite extremity of said slot when said lever has been moved from the first extremity thereof, so as to bring said switch points into resilient engagement with their respective rails; and means for manually imparting the initial rotation to said switch stand.
